UNITED STATES PATENT OFFICE.

WILLIAM CRISTVON MEYER, OF BEVERLY, MASSACHUSETTS, ASSIGNOR TO UNITED SHOE MACHINERY COMPANY, OF PATERSON, NEW JERSEY, A CORPORATION OF NEW JERSEY.

INSEAM SHOE-SEWING MACHINE.

Application filed June 27, 1919. Serial No. 307,127.

To all whom it may concern:

Be it known that I, WILLIAM C. MEYER, a citizen of the United States, residing at Beverly, in the county of Essex and State of Massachusetts, have invented certain new and useful Improvements in Inseam Shoe-Sewing Machines; and I do hereby declare the following to be a full, clear, and exact description of the invention, such as will enable others skilled in the art to which it appertains to make and use the same.

This invention relates to sewing machines of the class employed in sewing inseams of shoes.

15 The object of the invention is to improve the construction and mode of operation of certain parts of the work supporting mechanism in shoe sewing machines of the above class.

20 With this object in view the features of the invention consist in certain novel and improved constructions, arrangements and combinations of parts hereinafter described and particularly pointed out in the claims, the 25 advantages of which will be readily understood and appreciated by those skilled in the art.

The features of the invention will be clearly understood from the accompanying drawings illustrating the invention in its preferred form and the following detailed description of the constructions therein shown.

30 In the drawings Figure 1 is a view in side elevation of a portion of an inseam shoe sewing machine embodying the invention; Fig. 35 2 is a detail view illustrating a portion of the mechanism shown in Fig. 1 partly in rear elevation and partly in section on the line 2-2 of said figure; Fig. 3 is a detail sectional view taken substantially on the line 40 3-3 of Fig. 2.

The invention is illustrated in the drawings as embodied in a machine having, except as hereinafter described, substantially 45 the same construction and mode of operation as the machine illustrated and described in applicant's pending application, Ser. No. 165,107, filed April 28, 1917. The machine shown in the drawings comprises an oscillating curved hook needle 2, a work feeding awl 4, a looper 6, a channel guide 8, a thread finger 10 and a back gage 12. The back gage is mounted on the forward end of a slide 14 which is moved forwardly to bring the back 50 gage into engagement with the shoe by the

action of a spring 16. The slide 14 is locked in forward position during a portion of each cycle of operations and is retracted to carry the back gage out of engagement with the shoe during the feeding of the shoe by means 60 of a clutch mechanism (not shown) which is actuated and controlled from a lever 18 pivoted on a shaft 20 secured in the frame of the machine. All of the parts thus far described have substantially the same construction, arrangement and mode of operation as 65 the corresponding parts of the machine illustrated and described in the above application.

The machine is provided with the usual 70 back rest 22 to assist in supporting the shoe during the sewing operation and the present invention is illustrated as embodied in the back rest mechanism. The back rest is mounted on the forward end of a slide 24 arranged for forward and rearward movement in suitable guides in the frame of the machine. The slide 24 is acted upon by a coiled spring 26 coiled about a boss 28 on the frame, one arm of which engages a fixed 75 abutment 30 on the frame and the other arm of which engages a pin 32 mounted on the slide 24. The slide 24 is also acted upon by a spring 34 one arm of which passes through an arm 36 formed on a plate 40 secured to the 80 frame and engages at its end a projection 42 on said plate, and the other arm of which engages a pin 44 mounted on the slide. The springs 26 and 34 normally press the slide 85 24 forwardly in its guides in the frame and cause the back rest to follow the contour of the shoe as the shoe is manipulated to present the same to the sewing mechanism. The forward movement of the slide 24 under the influence of the springs 26 and 34 is limited 90 by the engagement of a projection 46 on the frame extending into a slot 48 in the slide with the rear end of said slot.

During the greater part of each cycle of operations and, preferably, at all times except during the feeding movement of the shoe the back rest is locked against either forward or rearward movement. When the shoe is being fed the back rest is unlocked so that it can accommodate itself to the 100 position of the shoe. The locking of the back rest against rearward movement causes the same to furnish a rigid abutment to support the shoe during the formation of a stitch. The locking of the back rest 105 110

against forward movement as the channel guide is actuated to disengage its acting end from the bottom of the channel prevents the back rest from then moving forward and displacing the shoe.

The locking mechanism for the back rest comprises a pair of clutch rolls 50 and 52 resting on the upper surface of the slide 24 and a locking lever 54 pivoted at 56 on the frame, the forward end of which engages and is supported by said rolls. The locking lever 54 is provided with an inclined contact face 58 for engagement with the roll 50 to lock the slide 24 against forward movement and with an oppositely inclined contact face 60 for engagement with the roll 52 to lock the slide against rearward movement. The rolls 50 and 52 are yieldingly held in position longitudinally of the locking lever by means of spring pressed plungers 62.

As long as the locking lever 54 is free to move upwardly the clutch rolls 50 and 52 allow the slide 24 to move forwardly or rearwardly. In locking the slide 24 the locking lever 54 is forced downwardly against the rolls 50 and 52 causing the rolls to grip the slide. The locking lever is forced downwardly against the clutch rolls by means of a roll 64 mounted on one arm of a lever 66 pivoted on the shaft 20, said roll being arranged to engage the upper face of the locking lever which is inclined slightly upwardly from its rear toward its forward end. The lever 66 is swung forwardly to cause the roll 64 to force the locking lever downwardly and is swung rearwardly to release the locking lever. The lever 66 is actuated from the lever 18. The lever 66 is swung forwardly from the lever 18 as the lower arm of the latter lever swings forwardly through a spring 68 interposed between a projection 70 on the lever 66 and a projection 72 on the lever 18. The lever 66 is swung rearwardly as the lower arm of the lever 18 swings rearwardly through the engagement of an abutment screw 74 threaded into a projection 76 on the lever 66 with the projection 72 on the lever 18. The parts are constructed and arranged so that the locking lever 54 is actuated to lock the slide 24 and the forward movement of the lever 66 is limited by the engagement of the roll 64 with the locking lever before the lower arm of the lever 18 completes its forward movement, the spring 68 being compressed during the continued forward movement of the lower arm on the latter lever. This insures the actuation of the parts of the locking mechanism in a reliable manner to lock the slide 24 even when the parts have become considerably worn by continued use, and eliminates the necessity of frequent adjustment of the parts to take up wear. The extent to which the lever 66 is swung rear-

wardly to release the locking lever may be adjusted by adjusting the abutment screw 74.

Although the invention has been illustrated in the present application as embodied in a back rest mechanism for inseam sewing machines, certain features thereof are not limited to this particular mechanism but may be embodied with advantage in a back gage or welt guide mechanism for machines of this class.

Having explained the nature and object of the invention, and having specifically described a machine embodying the invention in its preferred form, what is claimed is:

1. An inseam shoe sewing machine having, in combination, stitch forming devices including a curved hook needle, a forwardly and rearwardly movable slide, a shoe support mounted to move with the slide, means for moving the slide longitudinally and means for locking the slide from forward or rearward movement during each cycle of operations comprising two locking rolls for engaging the slide, a locking member having oppositely inclined faces arranged respectively to engage the rolls simultaneously, and means operating to press said member toward the rolls and to release the same during each cycle.

2. An inseam shoe sewing machine having, in combination, stitch forming devices including a curved hook needle, a forwardly and rearwardly movable slide, a shoe support mounted to move with the slide, means for moving the slide longitudinally and means for locking the slide during each cycle of operations comprising a locking roll for engaging the slide, a locking lever having on one side an inclined face for engaging the roll, a reciprocatory member arranged during its movement in one direction to press the lever laterally toward the roll and during its movement in the opposite direction to release the lever, and means for moving said member yieldingly in the first direction and for moving said member in the latter direction.

3. An inseam shoe sewing machine having, in combination, stitch forming devices including a curved hook needle, a forwardly and rearwardly movable slide, a shoe support mounted to move with the slide, means for moving the slide longitudinally and means for locking the slide during each cycle of operations comprising a locking roll for engaging the slide, a locking member having an inclined face for engaging the roll, an oscillatory lever, a roll carried by the lever and arranged to engage the locking member and force the same toward the roll during the movement of the oscillatory lever in one direction and to release the locking member during the movement of the oscillatory lever in the opposite direction, an ac-

- tuating lever pivoted co-axially with the oscillatory lever, a spring interposed between said levers through which the oscillatory lever is moved from the actuating lever in the first direction, and an abutment screw threaded into the oscillatory lever and arranged to engage the actuating lever through which the oscillatory lever is moved from the actuating lever in the latter direction.
- 10 4. An inseam shoe sewing machine having, in combination, stitch forming devices including a curved hook needle, a forwardly and rearwardly movable slide, a shoe support mounted to move with the slide, means for moving the slide longitudinally and means for locking the slide during each cycle of operations comprising a locking roll for engaging the slide, a locking lever having an inclined face for engaging the roll, an oscillatory lever, a roll carried by the lever arranged to engage the locking lever and force the same toward the roll during the movement of the oscillatory lever in one direction and to release the locking lever during the movement of the oscillatory lever in the opposite direction, the locking lever having a contact face for engagement with the roll inclined in the direction of movement of the roll.
- 15 5. An inseam shoe sewing machine having, in combination, stitch forming devices including a curved hook needle, a forwardly and rearwardly movable slide, a shoe support mounted to move with the slide, means for moving the slide longitudinally, roll clutches for simultaneously locking the slide from forward or rearward movement during each cycle of operations comprising a locking member having oppositely inclined roll engaging faces, and means operating to move said member into and out of locking position during each cycle.
- 20 6. An inseam shoe sewing machine having, in combination, stitch forming devices including a curved hook needle, a forwardly and rearwardly movable slide, a shoe support mounted to move with the slide, means for moving the slide longitudinally, a slide clutching device, and means for actuating said device during each cycle of operations to lock the slide simultaneously against forward and rearward movement.
